UNITED STATES PATENT OFFICE

CHARLES AMÉDÉE CAMBAY, OF PARIS, FRANCE
AUTOMATIC COIN CONTROLLED TELEPHONE APPARATUS

Original application filed October 27, 1927, Serial No. 229,071, and in France October 6, 1927. Divided and this application filed January 3, 1929. Serial No. 330,002.

The invention relates to coin-controlled mechanism for telephones for use in local and suburban telephoning, and has for its object the use of two different coins or tokens corresponding to different tariffs. The mechanism is operated by the user of the telephone without intervention of the central exchange operator.

The mechanism prevents fraudulent use, and is free from errors of operation, and includes in combination arrangements as follows:

(a) Means to control the introduction of the coins by closing the coin slot if the receiver is not on the hook:

(b) Means operated to close the first slot after a coin has been inserted, and open a second slot:

(c) Mechanism for locking and unlocking the receiver hook, the unlocking being effected by inserting a coin, and the locking by hanging up the receiver on its hook:

(d) Tilting mechanism to support the coins after insertion:

(e) Electro-magnetic mechanism to tilt the coin mechanism to retain or return the coin, operated by talking current to retain the coin when the user unhooks the receiver.

(f) Mechanism to operate the tilting mechanism to return the coin when the receiver is hung up.

(g) A registering mechanism to register or count the coins retained.

(h) An auxiliary microphone to transmit the sound of a bell, sounded by one of the coins, to the central station.

(i) Mechanism to return all of the parts to normal position by the hanging up of the receiver.

(j) Mechanism to render the auxiliary microphone inoperative when communication has been established.

(k) Mechanism to prevent fraudulent use after communication has been established.

(l) Means to communicate with the central operator when the wrong subscriber has been connected.

The combination of these various mechanisms is effected by two movable plates, an upper and a lower plate, having sliding

connection between them, such that their ascending movements are independent but the descent of the upper plate returns the lower plate to normal position. The upper plate is connected to the telephone hook and controls the mechanisms *f*, *g*, *i* and *b* indicated above, for locking *a* and *c*.

The lower plate during its rise, which is effected by a spring, is retained in normal position by an armature of a polarized electro-magnet through which a reverse current is sent when the called subscriber takes down his receiver and releases the lower plate.

The ascent of the lower plate controls the mechanism in *e*, *j* and *k*, supra, and contact means to place the electro-magnet out of circuit.

In the drawings, in which like parts are similarly designated—

Fig. 1 is a front elevation of a telephone provided with an apparatus according to the present invention.

Fig. 2 is a side elevation.

Fig. 3 is a front elevation of the auxiliary microphone control.

Fig. 4 shows the whole of the apparatus after a second check or coin has been inserted in the opening, designed for the suburban calls and before collecting the coins.

Figs. 4^a, 4^b show two positions corresponding to that of Figs. 3 and 4 of the operation effected by the second coin or check to change the position of the upper contact blades which put the auxiliary microphone in the circuit.

Fig. 5 shows the position of the lower contacts for placing the electro-magnet out of circuit.

Figs. 6 and 6^a show the double opening for the introduction of the coin with the obturating means.

Figs. 7, 7^a show the same opening the obturating means closing the right hand opening.

Fig. 8 shows the locking motion when the telephone receiver has been taken down.

Fig. 9 is a similar view with the receiver on the hook.

Figs. 10, 11, 12 show the ejecting mechanism the collecting mechanism, the driving system for the registering devices and a mechanism for the second locking in different positions.

Figs. 13, 14 and 15 show an arrangement of the push button for use in case a wrong connection has been made.

Figs. 16, 17 show two different positions 10 of the polarized electromagnet mounted at the base of the apparatus which allows of altering the contact of the lower and the upper blades when the current has been reversed and of collecting one or several 15 checks or coins.

Fig. 18 shows a diagram of the circuit of the apparatus.

In the mode of execution represented in Figs. 1 to 18, the apparatus comprises two 20 openings 6^b 6^c for Figs. 6^a and 7^a the introduction of the coins the right hand one of which is always open when the apparatus is not in use, as will be seen in Fig. 6^a in order to allow the introduction of a coin 25 when it is desired to make a town call, the left hand one being closed and opening only (Fig. 7^a) after the first coin has been introduced in the right hand opening, the left hand opening being designed for the 30 introduction of a second coin only when it is desired to make a suburban call.

When a coin or check 15 has been introduced in the opening 6^b as it falls in the chute 6 it must engage the extension 7 of 35 a rocking lever which in its normal position of rest occupies the position shown in Fig. 9 when the receiver is well hung on the hook, the arm 7^a of said lever being heavier than the arm 7. The horizontal 40 position is also facilitated by the action of the hook 16^a of plate 16 upon the heel 7^c when the receiver is put back. In this position the upper movable plate 16 is locked by the hook 48 of an oscillating part 49 45 which is acted upon by a spring 50. The movable plate 16 is provided with a perforated part 47 secured upon it by means of a screw 46 and through which perforation the telephone hook passes. When the 50 receiver is hung up the hook 48 being substantially opposite a projection 16^a of the part 16 prevents the latter from going up when the receiver is taken from the hook if a coin has not been previously inserted 55 in the opening 6^b. In this inoperative position the projection 16^a is brought under the hook 48 by the action of an abutment 7^b of the lever 7 engaging the bottom of the groove 49^a of the part 49 as will be seen in 60 Fig. 9 and locks the hook 48 in its suspended position. When the introduction of the coin which operates the rocking of the lever 7 has been effected as shown in Fig. 8, the abutment 7^b rises again and unlocks the part 49 which owing to the action 65

of the spring compels the projection 16^a to free the hook 48; the receiver may then be taken off the hook and consequently the part 47 and the movable plate 16 may move upwards as will be seen in Fig. 8.

In the case of the receiver not being well hung on its hook (Fig. 7) the passage of the check 15 through the opening is prevented by an abutment 50 passing through the opening. This abutment is integral with a 70 part oscillating at 51 acted upon by a spring 52 and upon which an arm 53 with a hook is pivoted. When the receiver is not well hung on the hook the arm 53 is free and the spring 52 pushes the abutment 56 in the coin chute. On the contrary when the receiver is well hung up a pin 54 carried upon the part 47 with which the receiver arm 4 is engaged acts upon the arm 53 and the latter being pulled down compels the abutment 50 to oscillate in such a manner that it no longer projects in the chute.

Figs. 6, 6^a, 7, 7^a show a self operating closing device for the admission openings. It is constituted by an oscillating shutter 54^a having its axis connected to a connecting rod 55 actuated by a rod 56 passing loosely through an extension 57^a secured to the part 47 and provided with two springs 58, 58^a on either side of the extension 57^a. After 90 the introduction of a coin or a check in the right hand opening 6^b (Fig. 6^a) which is normally open when inoperative, and the receiver having been taken off the hook, the part 47 moves up, the lower spring 58^a which was slightly compressed by the extension 57^a is first distended, the latter then compressing the upper spring 58 until it acts upon the ring 59^b of the rod 56, this ring in its upward movement actuating the connecting rod 55 which brings the shutter 54 in the position shown in Fig. 7^a when the right hand opening designed for the town call is closed and the left hand opening, in which a second check must be inserted to 100 make a suburban call is opened.

When the receiver is put back the extension 57^a comes to bear upon the lower spring 58^a and when the compression is sufficient the rod 56 comes down and operates the shutter 54 which then returns to the position shown in Fig. 6^a.

It will consequently be understood that it is absolutely necessary to insert the check in the right hand opening which is the only one open in order to make a town call, the left hand opening reserved to the second check for the suburban calls being open only when the receiver has been taken off the hook, the right hand one being then closed.

The rocking device 13 carrying the two pins upon which the check 15 falls temporarily in the case of a town call or two checks fall side by side in the case of a suburban call, may rotate upon an axis 14 carried 130

5 by the bottom plate (Figs. 10, 11, 12). This rocking device comprises also two controlling pins 30, 31, the first being actuated only for returning or giving back the coin when the connection has not been made and the second pin 31 acting to prepare for collecting of the coin when the connection asked for has been obtained.

10 Fig. 10 shows the rocking device in the normal position the two checks which have been introduced according to the case in view resting upon the two pins 12. When the desired connection has not been made the user puts back the receiver, the part 16 falls 15 down taking along a spring pivoted abutment 57 mounted on it. The abutment then acts upon the pin 30 thus compelling the rocking device 13 to take the position shown in Fig. 11 and the check or the checks 15, 15 20 are returned out of the apparatus at 6a. Owing to its spring the abutment 57 may clear the pin 30 when its operation is ended.

25 If the desired connection has been obtained the lower movable plate 59 rises under the action of its spring 59a, being released, as will be explained later. This plate is provided with an inclined surface 60 located above a groove 60a which as it comes to act upon the pin 31 causes the rocking device 30 30 31 to oscillate and come in the position shown in Fig. 12 which corresponds to preparing for collecting the coin, the notch 60a retaining the rocking device in this position up to the moment when the receiver is put 35 back.

When the rocking device 13 is in this position every coin is retained between a stationary abutment 61 and a lever 62 pivoted at 63 upon the back plate; the apparatus 40 comprises a single abutment 61 and two levers 62, one for the town calls and the other for the additional coin which is required in order to obtain the suburban connection.

45 Finally the coins or checks fall in the till when the receiver is put back on the hook at the end of the conversation, this taking place as will be seen further by the coming down of the moving part 16. When 50 the rocking part 13 has reached in its movement the position indicated in Fig. 12, the coin or coins 15 which have taken their position as above mentioned between the abutment 61 and the inner edge of one of several 55 levers 62 are situated under an abutment 64a carried by a curved lever 64 pivoted at 65 upon which acts a spring 66.

When the connection is ended the user 60 puts back the receiver, the movable part 16 descends and its inclined surface 16b engages a roller 67 carried by the lever 64, causing same to move down, the coin or coins 65 being pressed down by the abutment 64a in such a manner that they push back one of the levers 62 or both of them being

pivotedly connected to a connecting rod 68 which actuates a driving finger 69 of the corresponding registering device 70, the various parts are returned in their respective positions by springs 71 after the passage 70 of the coin or coins which fall in the till.

A secondary microphone 72 and a bell 73 are provided in the upper part of the apparatus. The sound emitted by the bell is transmitted by the microphone to the operator at the exchange office when a second coin or check has been introduced in the left hand opening with the object of establishing a suburban connection (Figs. 3 and 4). The secondary microphone may 80 be put in or out of circuit by means of a pair of stationary contact blades 74, 75 and of a middle movable blade 76, the latter when in its inoperative position being in contact with the left hand blade 74 and 85 the secondary microphone being out of circuit.

When the user inserts a coin in the left hand opening (Fig. 4a) it comes upon the projection 77 of a part rotating upon an 90 axle 79 and connected to a rod 80 herein-after described, the part 78 coming now in the position shown in Fig. 4b thus compelling its edge to push the middle blade 76 to the left that is to say against the blade 95 75 thus putting the secondary microphone in circuit and consequently allowing the switch board operator to hear the sound of the bell produced by the impact of the check against it. 100

The apparatus is provided at its lower part with a polarized electromagnet 58 which draws an armature 80a when a reversal of current takes place when called subscriber has taken down his receiver, as shown in 105 Fig. 17 said armature being integral with a lever 81 which carries a shaft 82 provided with a hook 82a designed to maintain in a stationary position a shaft 83 integral with the movable plate 59 (Fig. 16). When the 110 current is reversed in said electromagnet, the armature 80a is attracted, the hook 82a frees the rod 83 which is integral with the movable plate 59 this plate being now drawn upwards by its spring 59a. 115

The apparatus is also provided at its base with two stationary contact blades 84, 85 and one movable middle blade 86 (Figs. 4 and 5) acted upon by a cam 87a actuated by means of a rod 88 drawn in its movement by the movable plate 59. 120

When the middle blade is in its inoperative position it engages the upper blade 85 (Fig. 4) and when the current has been reversed that is when the plate 59 has effected 125 its upward movement the middle blade contacts with the blade 84 (Fig. 5) thus short circuiting the electromagnet during the conversation.

The rod 80 is not actuated for the town 130

conversation by the upward movement of the movable plate 59 because the abutment 59^b of the latter cannot reach during its upward movement the collar 80^a as indicated in Fig. 5; this will be easily understood as the rod 80 has not moved down for the reason that a second check has not been introduced in the apparatus; the rocking element 86^a is also in the position shown in Fig. 5 and retains the shaft in its raised position by means of a spring 87. It will also be seen that the end 86^b passes around the rod 80 under a ring loosely surrounding the latter and provided with a spring 88^a which bears upon a shoulder 80^b on the shaft.

It has already been stated that in the case of suburban connections the introduction of a second check or coin produces the downward movement of the shaft 80 and the oscillation of the blade 86 when they come in the positions shown in Fig. 5. When the current has been reversed that is when the desired connection has been made in addition to the change in the lower contacts the following operation takes place; the abutment 59^b of the plate 59 which is drawn upward by its spring 59^a operates under the collar 80^a of the rod 80 which it raises and altering the position of the upper contact puts the secondary microphone in short circuit.

In the case when the user cannot be connected with the suburban line, the reversal of the current has not taken place and consequently the plate 59 remains in its lower position but the rod 80 has been depressed by the introduction of the second coin and the blade 86 is in the position indicated in Fig. 4.

It is therefore necessary to return the upper contacts in the position for starting in order to put the secondary microphone in circuit for the next conversation.

This is effected by putting back the receiver when owing to the downward movement of the movable plate 16 its element 16^a imparts an oscillating movement to the blade 86 causing the rod 80 to move upwards and the part 78 to return to its position in Fig. 4^a, instead of that in Fig. 4^b which it occupied previously.

The movable plate 59 has also for its function as it moves upwards when the current has been reversed to draw along the rod 90 by means of its upper abutment by the intermediary of a spring 91 the head of said rod coming under the portion 16^c of the movable plate 16.

When the receiver is put back the abutment 16^c drives the rod 90 of which the lower portion 90^a coming to bear upon the end of the oscillating hook lever 81 (Fig. 16) ensures a good suspension of the receiver.

The ascending movement of the movable

part 59 operates also a second locking of the movable plate 16 which completely prevents another call being made. The plate 59 is provided to this end at the top with a rod 91 carrying between two springs 92 the operating blade 93 of an oscillating bolt 94. During the ascending movement the lower spring being compressed rotates the bolt 94 in such a manner that its portion 94^a comes to bear against an abutment 95 integral with the plate 16; as soon as the receiver hook is depressed, the plate 16 moves downwards, the bolt rotating still further when the abutment 95 comes under the portion 94^a and the latter coming above the abutment prevents the rising of the plate 16 and consequently of the receiver hook.

In the position shown in Fig. 10 the second locking is not actuated because the plate 59 has not been displaced as the reversal of the current has not taken place in the electromagnet 58. In the arrangement shown in Fig. 12, the bolt 94^a is shown in its position prior to the locking, the inner contacts of the telephone being in the required position for making the connection, the locking is effected only when the hook is slightly depressed in order for instance to make an attempt to call after a conversation without introducing another coin in the apparatus. During this movement the abutment is in a position slightly under the one it occupied previously and will consequently prevent the receiver hook from rising sufficiently high to close the conversation circuit; a second call when the talking is ended being thus rendered impossible as the first locking by 25 takes place when the receiver is put back through the depression of the movable plate 16, the depression of the plate 59 then producing only the upper unlocking.

It will be noted that the rising movements of both movable plates 16 and 59 are independent, that of the plate 16 being produced by the inner return spring of the hook 4 and that of the plate 59 by the traction of the spring 59^a when the reversal of the current has disengaged the hook 82^a from shaft 83.

At a certain moment on the contrary their downward movement is conjugated owing to a slot 96 in plate 59 engaging a dowel pin 97 provided on plate 16. When the receiver has been taken off the hook the plate 16 rises completely. On the reversal of current taking place, the hook 94 frees the rod 93 and the plate 59 drawn along by its spring 59^a rises to the end of its movement until its slot 96 engages the dowel pin 97.

When the conversation has ended the receiver is put back, the plate 16 comes down bringing with it the plate 59 by the intermediary of the dowel pin 97 which engages the bottom of the slot 96.

To the apparatus which has just been described there is added a device which allows

of calling again the switchboard operator at the exchange office before putting back the receiver when a wrong number has been given. This device which is shown in the 5 Figs. 13, 14, 15 of the appended drawings comprises a push button 98 drawn outwards by a spring 99 and provided inside with a projecting sharp edge 100 engaging a small roller 101 integral with a contact blade 102 which allows of breaking rapidly and intermittently the contact with a second stationary blade 103.

The intermittent depression of the push knob 98 produces only intermittent flashes 15 to one side or the other, thus making the fact that the roller 101 cannot remain upon the sharp edge 100 but necessarily falls off to one side or the other, thus making the contact as soon as it is interrupted and 20 totally preventing a lengthy interruption of the current.

The diagram of the electric wiring shown in Fig. 18 illustrates the various connections: 104, 105 are the line conductors, the 25 contact blades being in the inoperative position.

The mode of operation in the case of a suburban connection is as follows:

The opening on the left hand of the apparatus being closed, the user inserts in the right hand opening 6^b (Fig. 6) a check or coin which as it falls rotates the rocking device 7 thus preventing the operation of the bolt 48 which locked the plate 16 in its lower 30 position, the coin falling temporarily upon the rocking device 13, he then takes the receiver from the hook allowing the plate 16 to move upwards and thus producing the call contact at the office, the closure of the 35 opening 6^b and the opening of the opening 6^a.

In the event of town calls two different cases may be foreseen:

(a) The desired number is busy or the 45 call remains unanswered. The coin resting temporarily upon the rocking device the coin will be returned to its owner by simply putting back the receiver. In reality the movable part 16 moving downwards, the 50 spring abutment 57 which it carries acts upon the pin 30 of the rocking device and causes the latter to come in the position shown in Fig. 11 so that the check is ejected at 6^a.

(b) The connection is made. The caller having inserted a coin and taken the telephone off the hook the subscriber who has been called has taken his receiver off the hook. At that instant, the current is reversed the polarized electromagnet 58 operates, the armature 80 is drawn, the hook 82^a draws back (Fig. 17) thus disengaging the part 83 which is integral with the movable plate 59, which being no longer locked is 60 moved upwards by its spring 59^a and as it

ascends the inclined surface 60 and its notch 60^a engage the pin 31 of the rocking device 13 which rotates and comes in the position shown in Fig. 12, preparatory to collecting the coin which cannot be ejected at that 70 moment.

When the conversation has been ended the receiver is put back on the hook, the part 16 moves down and its inclined surface 16^b comes to act upon the roller 67 of the curvilinear part 64 causing the coin to come between the stationary projection 61 and the oscillating lever 62 which actuates the counting device to which it is connected. 75

The hanging back of the receiver also 80 actuates the part 56 which closes the left hand opening and uncovers the other.

The mode of operation in the case of a suburban connection is as follows:

The user having inserted a coin in the 85 right hand opening which is open, the operations are the same as indicated in the case of a town call. The receiver having been taken down the connection is made with the telephone exchange and a suburban connection is asked for. The telephonist then instructs the caller to insert a second coin which he must necessarily put in the left hand opening which is the only one open. 90

The introduction of the second coin actuates the cam 78 which changing the upper contacts puts the secondary microphone 72 in the circuit. Another effect produced being that the coin in its fall strikes upon the bell 73 which gives a sound that is reproduced by the secondary microphone and may therefore be heard by the telephonist who is thus informed that a second coin has been introduced in the apparatus. 95

From that instant, two different cases 100 may arise:

1st. Either the desired number is not free or the subscriber does not answer.

It will then be sufficient to put back the receiver to have both coins ejected. On the other hand the putting back of the receiver causes the rod 80 to move upwards under the action of the part 86^a, 86^b thus compelling the upper contacts to return to their first position in such manner that the secondary microphone is short-circuited. 115

2nd. The desired connection has been made. When the two coins having been successively introduced in the apparatus as previously indicated for the first case the telephonist has given the required connection, the current is reversed in the electromagnet with the following results:

1. The movable plate 59 as it is drawn upwards by its spring 59^a rotates the rocking part 13 upon which the two coins rest temporarily and compels it to come in the position shown in Fig. 12 which is that of pre-cashing. 125

2. This same plate 59 carries the rod 80 130

upwards and the latter by the intermediary of the cam 78 alters the relative position of the upper contacts and consequently puts the secondary microphone 72 in short circuit.

5 3. The upward movement of the plate 59 actuating the cam 87^a has also altered the position of the lower contacts to put the polarized electromagnet 58 in short circuit. The conversation therefore takes place in 10 the same manner as on an ordinary line. When the conversation has ended and the user puts back the receiver the coins are pushed simultaneously in the till and on 15 their passage they both operate a counting device.

When the user is called he can answer by putting a coin in the right hand opening and as there is no reversal of the current the coin is returned when he puts back the 20 receiver and without the counting device having been operated.

25 What I claim and desire to secure by Letters Patent of the United States is:

1. An automatic telephone apparatus for 25 single and double tariff which comprises two openings for the introduction of the coins, two chutes, a rocking lever on which the coins fall, a rocking lever for the suspension arm of the receiver, a balanced rocking device, two pins upon same to temporarily receive the coins, pins designed to operate the rocking device, an obturating shutter for closing the first opening when the first coin has been introduced and for uncovering the second opening when the receiver is taken off the hook, a mechanism for closing the second opening and opening the first when the receiver has been put back; an upper movable plate for carrying the 40 locking lever, a pivoted abutment in the coin chutes to prevent the coins from falling down in order to prevent the operation of the unlocking mechanism when the suspension of the receiver has not been completely effected, a spring pawl carried by the upper movable plate designed to act upon one of the pins of the rocking device when the receiver is put back in order to allow of recovering the coin or coins, a polarized electromagnet locking a lower movable plate 45 when in the inoperative position and actuated by a current reversal when the desired connection has been obtained, a driving spring for said movable plate, an inclined surface and a groove on said plate to actuate the second pin of the rocking device which then comes in a pre-cashing position, means to push down the coin or coins temporarily retained, a secondary microphone 50 which is only put in circuit by the insertion of a second coin, a bell upon which the coin falls, upper contacts for the secondary microphone, lower contacts for the polarized electromagnet, and means to retain the polarized electromagnet in suspended position.

2. An automatic telephone apparatus for single and double tariff comprising two openings for the introduction of the coins, two chutes, a rocking lever upon which the coins fall, a locking lever for the suspension arm of the receiver, a balanced rocking device to support temporarily the coin, two other operating pins for the rocking device, means to cause the oscillation of the rocking device, a shutter of obturating the first opening when a coin has been introduced in same and for uncovering the second when the receiver is taken off the hook, a spring shaft operated by the rising of the arm support of the receiver for actuating the shutter, an upper movable plate carrying the locking lever, a pivoted abutment for preventing the unlocking when the receiver has not been well hung on the hook, a polarized electromagnet for engaging when at rest a lower movable plate, a driving spring for said movable plate a secondary microphone, contacts for the putting in circuit of the secondary microphone by the oscillation of a cam put in action by the passage of a second coin, a spring shaft actuated by the passage of a second coin, a spring shaft actuated by the downward movement of the upper movable plate to change the upper contacts in order to put the secondary microphone in short circuit when the connection has not been made a bell upon which the second coin falls, lower contacts for the polarized electromagnet, means to alter the position of the lower contacts, means to maintain the suspension of the polarized electromagnet.

3. An automatic telephone apparatus for single and double tariff comprising two openings for the introduction of the coin, two chutes, a rocking lever upon which the coins fall, a locking lever for the suspension arm of the receiver, a balanced rocking device to support momentarily the coin, two other pins adapted for actuation by the electromagnet of the rocking part, means to rotate the rocking part, a shutter for closing the first coin opening when a first coin has been inserted in it and for uncovering the second opening when the receiver is taken off the hook, a spring shaft to move the shutter, an upper movable plate carrying the locking lever, a pivoted abutment preventing the unlocking of the movable plate when the receiver has not been completely hung, a polarized electromagnet locking in its inoperative position, a lower movable plate, an armature for said electromagnet put in action by the reversal of the current, a hook integral with the armature to prevent when in the inoperative position the ascending movement of a lower movable plate, an operating spring for said movable plate, a secondary microphone, contacts to put in circuit the secondary mi- 130

crophone, means for short-circuiting same, a bell upon which the second coin falls, lower contacts for the polarized electro-magnet, a lower cam actuated by the ascent 5 of the lower movable plate to put the polarized electromagnet in short circuit after the passage of the reversed current, and means to maintain the suspension of the polarized electromagnet.

10. 4. An automatic telephone apparatus for single and double tariff which comprises: two openings for the introduction of the coins, two chutes, a rocking lever upon which the coins fall, a locking lever for 15 suspension hook of the receiver, a balanced rocking device, two pins on same to temporarily support the coins two other pins to actuate the rocking device, means to rotate said rocking device, a shutter for closing the first opening when a first coin has 20 been introduced and for uncovering the second opening when the receiver is taken off the hook, means to operate the shutter, a movable plate for rotating the locking 25 lever, a polarized electromagnet for locking a lower movable plate when in its inoperative position, an armature for said electromagnet put in action by the reversal of the current, a hook integral with the armature to 30 prevent the rising of the lower movable plate when in its inoperative position, a driving spring for said movable plate, a secondary microphone, contacts for putting 35 said secondary microphone in circuit, means for short-circuiting said secondary microphone, a bell upon which the second coin falls, lower contacts for actuating the polarized electromagnet when the current has 40 been reversed, a shaft operated by the downward movement of the lower movable plate to retain the armature of the polarized electromagnet in its suspended position.

5. In an automatic telephone apparatus, 45 a plurality of coin chutes, mechanism to control the introduction of coins into the chutes mechanism for locking the telephone hook and operated by it, a coin controlled mechanism for unlocking the hook, a pivoted coin 50 receiver for the coins dropped into the chute, electro-magnetic means to tilt the coin receiver to retain the coin or coins and operated by talking current, means to operate the coin receiver to return the coin or coins 55 and actuated from the telephone hook when the electro-magnetic mechanism remains inoperative, a device to notify the central station that another coin has been deposited, means to place said device out of operation 60 when communication has not been established, and means also to bring said apparatus to a position of rest when communication is established.

6. An automatic telephone apparatus as 65 in claim 5 in which the telephone hook lever

is connected to an upper plate moving in a straight line that controls the means for ejecting the coin or coins when said electro-magnetic means does not operate, said plate also controlling the means to place said signalling means out of operation, the coin introduction control means and the mechanism for locking the telephone hook. 70

7. Apparatus as claimed in claim 5, in which the coin receiving tilting means comprises a lower plate having rectilinear movement, a spring for actuating it, said plate being held against movement by said electro-magnetic mechanism and released by reversal of current therein when communication 80 has been established, said plate controlling during its movement in one direction the coin receiver to retain the coin or coins, a plurality of contacts, operated by said plate in an opposite direction to place said electro-magnetic mechanism out of operation and other contacts actuated by this plate to disconnect the device indicating the additional payment from the circuit. 85

8. Apparatus as claimed in claim 5, in which the means to control the introduction 90 of the coins comprises a pivoted shutter normally maintaining one of the chutes open, a rod connected thereto to swing the shutter from one chute to the next, a lever to which the rod is connected, a pivoted perforate plate through which the telephone hook lever passes, and means to yieldingly connect the rod and plate to operate the shutter in unison with the hook lever. 95

9. A slot closing mechanism for apparatus as claimed in claim 5, comprising a spring actuated lug pivoted to pass into one of the coin chutes, a perforated lever through which the telephone hook passes, and a pin 100 on said plate to operate the lug. 105

10. Apparatus as claimed in claim 5, in which the device to notify the central station includes a bell, a microphone and a plurality of contacts, and means to operate 110 said contacts actuated by the insertion of a coin to place said microphone in circuit, said coin thereafter striking said bell.

11. Apparatus as claimed in claim 5, in which the signalling device is provided with 115 contacts for placing it in and out of circuit, means for shifting the contacts comprising pivoted means actuated by a coin to close the contacts, a rod connected to said pivoted means, a lever for actuating said rod, a vertically movable plate operated by the telephone hook, and a lug on said plate to actuate the lever and raise said rod to place the microphone out of circuit in case communication has not been established. 120

12. Apparatus as claimed in claim 5, in which the signalling device is provided with contacts for placing it in and out of circuit, pivoted means for shifting the contacts and 130 actuated by a coin, a rod connected to said

pivoted means, an upwardly movable lower plate, a lug thereon to move said rod to normal position to restore the pivoted means and thereby the contacts to normal position and disconnect the signalling device after telephonic communication has been established.

In testimony that I claim the foregoing as my invention, I have signed my name.

10 CHARLES AMÉDÉE CAMBAY.
